UNITED STATES PATENT OFFICE.

RAPHAËL NETTER, OF NEW YORK, N. Y.; ADELAIDE FOLLET NETTER EXECUTRIX OF
SAID RAPHAËL NETTER, DECEASED.

ATTACHMENT TO SEWING MACHINES.

Application filed May 17, 1921. Serial No. 470,336.

To all whom it may concern:

Be it known that I, RAPHAËL NETTER, a citizen of the Republic of France, residing at New York, county of New York, and State of New York, have invented certain new and useful Improvements in Attachments to Sewing Machines, of which the following is a full, clear, and exact description.

10. Sewing machines at the present time are generally provided with attachments known as hemmers, which consist of spirally formed folding guides designed to be secured in advance of the needle and feeding mechanism which operate to fold over the edge of a piece of fabric before it reaches the needle to form a true hem or the edges of two superposed fabrics to form a fell.

Such devices usually require the work of 20 a skilled operative, as it is very frequently the case that the edges of the fabric are not cut exactly on a straight line or become distorted, so that in the absence of highly trained and skilled manipulation, the raw 25 edge will show at points under the folded edge of the hem, or such edge will not be properly turned under, and sewed. In this way unsightly or defective garments or hemmed articles are apt to be turned out 30 which have a correspondingly decreased value.

No mechanical attachment to a sewing machine had ever, to my knowledge, been produced which effectively and completely obviated this difficulty, although many attempts have been made to devise and operate such a device, until I designed and applied the corrective appliance for this purpose which forms the subject of this application 40 for Letters Patent. This new device as I have designed it, consists in a cutting device which is applied in front or in advance of the feed mechanism and needle and at the entrance to the folding guide, which cuts 45 from the raw edge of an introduced fabric a narrow strip, along a line which leaves a straight edge or has always a definite relation to the folded edge that passes to the needle.

Practical considerations require that such 50 a cutting device be operated by the machine itself and at a proper speed; that it occupy but little space; that it shall be capable of long-continued use without attention, and that it be so designed and operated that it 55 takes from the operative the burden of skillful manipulation. These are problems that have been by no means easy of solution, but I have succeeded in solving them and producing a simple, durable and very highly 60 efficient attachment for the purpose.

In carrying out this invention I attach in any suitable manner to the machine a cutting device having a fixed and an oscillating or reciprocating member, at or near the 65 point where the introduced fabric enters the folding spiral of the hemmer guide. The proper movement of the reciprocating member is secured by connections hereinafter described, to a suitable member of the sewing machine, such as the rocker shaft which usually lies under the table and which raises the movable member of the feed mechanism, and these connections are so constructed and 70 designed that the reciprocating cutter member is moved to cut the fabric while the feed mechanism of the machine is at rest.

This improved attachment I have shown in detail in the accompanying drawings, in which:

Figure 1 is a sectional view of the essential parts of a sewing machine showing the improved attachment applied thereto.

Fig. 2 is a sectional detail of the cutter device and associated parts on the line 2—2 85 of Fig. 3.

Fig. 3 is a top plan view of the parts shown in Fig. 1, and

Fig. 4 is a vertical detail on the line 4—4 90 of Fig. 3.

The improvement is concerned incidentally only with the plan of construction of the sewing machine as a whole, and that shown may be regarded as typical of the form to which it is or may be applied. In 95 such machine 1 is the table, 2 is the presser foot, 3 is the needle under which is the proper feed mechanism, and under the table,

in this case, are two rocker shafts 4 and 5, the former oscillating the feed bed 6, the latter raising the same, in a manner familiar to all who are skilled in the art.

- 5 When this or any similar sewing machine is to be used to hem, a suitably formed spiral folder guide 7 is secured to the table in advance of the feed mechanism and needle, and in using this device the edge of the fabric to be hemmed is passed into the guide until it is taken hold of by the oscillating and reciprocating feed bed and thereby passed under the needle. In passing through the guide 7 the edges are folded under and over so that the line of stitches is along the folded portions and the latter issue as a true hem.

As above stated, the raw edge of the fabric is apt to be uneven with resulting imperfections in the finished hemmed edge. I therefore secure to the table in any proper manner, as by screw 8, a U-shaped support 9 in which is secured by a screw 10 the stationary member 11 of a cutting device. These parts are secured at the entrance to the spiral folder guide 7, the edge of the member 11 being adjusted properly with reference to the movable member of the cutter 12, so that the line of cut will be sufficiently into the fabric to take care of any irregularities that are likely to occur in the raw edge.

The said movable member 12 is clamped, as by a screw 13, to the arm 14 of a rock shaft 15 passing through a cylindrical guide 16. A nut 17 through which said shaft passes is screwed into the end of this cylinder and between said nut and a shoulder on the rock shaft is a spiral spring 18, which exerts sufficient pressure upon the shaft to keep the knife blade 12 in proper position relatively to the fixed member 11.

The function of the rock shaft 15 is to oscillate or reciprocate the knife blade 12, causing it in cooperation with the stationary knife member 11 to cut the fabric during the intervals of rest of the said fabric. To effect such operation by power derived from the machine is a nice problem. The movements must be exactly timed and must occur with the same rapidity as the oscillations of the needle, and the most practicable way I have found for accomplishing this is to operate the movable knife by the intermittently moving rocker shaft 5, which lifts the feed bed 6. For this purpose, I secure to the said shaft 5 a bracket 19 by any suitable means, and connect the extended arm of such bracket by a link 20 with a lever 21, pivoted at 22 to a stationary part of the machine, and connect said lever 21 by a link 23 to an arm 24, fixed to the rock shaft 15.

By this means as the rocker bar 5 oscillates, an oscillatory movement of sufficient extent is imparted to the shaft 15 to operate the knife blade 12 and as the shaft 5 is stationary

at the moment when the feed bed 6 is at rest and the needle moving, the movements of the knife will be properly timed.

Certain special provisions and details are of prime importance and should be carefully taken into consideration. To vary the throw of the knife blade 12, for example, to compensate for possible wear or other contingencies due provision should be made for varying the point of connection between the link 23 and the lever 21. Again, in order that the line of cut should be at the proper point, the knife blade 12, as shown in Fig. 3, should be offset and enter a cut-away part in the side of the spiral guide 7 back of the opening or mouth of the said guide, which mouth serves to hold the fabric during the cutting operation while the top wall of the guide acts as a stripper. With this construction no special feed dog or other feed mechanism is required in advance of the cutter and guide. Furthermore, the said knife blade should be normally in such position that it will always lie over a corner of the stationary member 11 to insure the proper relative positions of these two members at all times. Finally, it will be observed that suitable provision is made for the adjustment of the tension of the spring 18, by the nut 17 and for the adjustment of the stationary knife member 11 with respect to the other parts with which it is associated.

With this machine, the edge of any fabric which is to be hemmed is passed into the guide 7 in the usual manner, and sufficiently under the knife to have the latter cut a narrow and straight edge strip from its raw edge. As soon as the feed mechanism takes hold of the fabric the work of the operative ends and the further action becomes purely automatic. As stated above, if two pieces of fabric are to be united by a fell, their superimposed edges are passed into the guide and the same operation results. None of these operations calls for more than ordinary skill.

It is not essential that the knife blade be operated by the specific means herein shown, although these are the most practicable that I have thus far found. Nor is the invention limited to the specific form or character of the means employed for carrying out the desired and stated objects of my invention.

What I claim is:

1. The combination with a sewing machine and a hem folding guide, attached thereto, of a reciprocating knife located in advance of the needle and in a cut-away portion in the side of said guide back of the mouth of the same, and means driven by a moving part of the sewing machine for reciprocating said knife so that it will cut off from a fabric introduced into the guide a narrow straight edge strip.
2. The combination with a sewing ma-

chine and a hem folding guide attached thereto, of a cutting device consisting of a stationary and an intermittently reciprocating blade located in a cut-away part in the side of said guide back of the mouth of the same, connections between said reciprocating blade and the intermittently oscillating rocker bar that lifts the feed bed, for oper-

ating the said blade during the intervals of rest of the fabric and means for adjusting 10 the relative positions of the two members of the cutting device and the throw of the reciprocating blade.

In testimony whereof I hereto affix my signature.

RAPHAËL NETTER.
